UNITED STATES PATENT OFFICE

158,073

COMBINED BRACE, WRENCH, T-WRENCH, AND RATCHET

Eugene A. Heschel, Vickery, Ohio, assignor to The
Bingham-Herbrand Corporation, Toledo, Ohio,
a corporation of Ohio

Application January 25, 1949, Serial No. 461

Term of patent 14 years

(Cl. D54—13)

To all whom it may concern:

Be it known that I, Eugene A. Heschel, a citizen of the United States and resident of Vickery, in the county of Sandusky and State of Ohio, have invented a new, original, and ornamental Design for a Combined Brace, Wrench, T-Wrench, and Ratchet, of which the following is a specification, reference being had to the accompanying drawing, forming a part thereof.

In the drawing, Fig. 1 is a perspective view of a combined brace, wrench, T-wrench and ratchet, showing my new design, and Figs. 2 and 3 are side and outer end views thereof, respectively.

The dominant features of my design are shown in full lines.

I claim:

The ornamental design for a combined brace,

wrench, T-wrench, and ratchet, substantially as shown and described.

EUGENE A. HESCHEL.
